W. J. THOMAS.
ADJUSTABLE HOLDBACK.
APPLICATION FILED NOV. 5, 1908.

920,219.

Patented May 4, 1909.

UNITED STATES PATENT OFFICE.

WILLIAM J. THOMAS, OF INGLEWOOD, CALIFORNIA.

ADJUSTABLE HOLDBACK.

No. 920,219.

Specification of Letters Patent.

Patented May 4, 1909.

Application filed November 5, 1908. Serial No. 461,238.

To all whom it may concern:

Be it known that I, WILLIAM J. THOMAS, a citizen of the United States, residing at Inglewood, in the county of Los Angeles and State 5 of California, have invented a new and useful Adjustable Holdback, of which the following is a specification.

The invention relates to improvements in adjustable hold backs.

10 The object of the present invention is to improve the construction of adjustable hold backs, more especially that shown and described in Patent No. 798,308, granted to me Aug. 29, 1905, and to arrange the ring, which 15 is connected to the hold back exteriorly of the thill, so as not to encircle the same.

A further object of the invention is to provide an adjustable hold back of increased 20 strength and durability, adapted to be easily 25 and cheaply manufactured and applied to a shaft or thill, and capable of facilitating a rapid, accurate and instantaneous adjustment of the hold back strap to enable the same to fit the various sizes of animals hitched to a vehicle.

Another object of the invention is to provide an adjustable hold back, adapted in the event of breakage of the swingletree or a similar accident, to automatically disconnect the hold back straps from the thills.

The invention also has for its object to facilitate unhitching by enabling an animal, after the traces have been unhitched, to step from a vehicle without dragging the same 35 after it.

With these and other objects in view, the invention consists in the construction and novel combination of parts hereinafter fully described, illustrated in the accompanying 40 drawing, and pointed out in the claims hereto appended; it being understood that various changes in the form, proportion, size and minor details of construction, within the scope of the claims, may be resorted to without departing from the spirit or sacrificing any of the advantages of the invention.

In the drawing:—Figure 1 is a perspective view of an adjustable hold back, constructed in accordance with this invention and shown 50 applied to a portion of a shaft. Fig. 2 is a longitudinal sectional view of the same, the hold back strap and the connecting ring being swung forward in dotted lines. Fig. 3 is a transverse sectional view on the line 3—3 of Fig. 2.

Like numerals of reference designate corresponding parts in all the figures of the drawing.

The adjustable hold back comprises in its construction a relatively fixed guide plate 1, consisting of a flat strip of metal provided with reduced tapered ends 2, which are secured by screws, or other suitable fastening devices to the inner side of a shaft or thill 3. The longitudinal guide plate is also secured 65 at intervals to the shaft or thill by means of screws 4, or other suitable fastening devices, and it is bent outward adjacent to each end at 5, spacing disks or washers 6 being interposed between the off-set portions and the 70 shaft or thill, as clearly illustrated in Fig. 2 of the drawing. The intermediate off-set or spaced portion receives a slide 7, constructed of sheet metal, or other suitable material and having its side edges bent inwardly to form 75 approximately L-shaped flanges 8, which embrace the side edges of the guide bar, as clearly illustrated in Fig. 3 of the drawing. The slide, which is adjustable along the guide bar, is readily removed therefrom at either 80 end thereof, the inwardly extending side flanges 8 being located beyond the plane of the disks or washers 6 and the fastening means for securing the guide bar to the shaft or thill. 85

The slide, which is adjustable backwardly and forwardly to arrange a hold back strap 9 in proper position to suit the size of the animal hitched to the vehicle, is provided with a vertical eye 10, formed by bending the 90 rear end of the slide back upon itself, and the terminal portions 11 of the metal are secured by rivets, or other suitable means to the slide to provide a structure of the requisite strength. The eye receives a swinging half 95 ring or D 12, which constitutes a coupling member for connecting the hold back strap with the adjustable slide 7.

The longitudinal guide is provided at intervals with longitudinal slots 13, and the 100 slide is equipped with a catch consisting of a flat spring 14, secured at its front end 15 to the slide by rivets, or other suitable fastening means and provided at its rear end with a longitudinal lug 16, extending through a 105 slot 17 of the slide and arranged to engage the slots 13 of the guide 1. The thill is also provided at intervals with tapered recesses 18, located adjacent to the slots and adapted to receive the projecting end of the lug. 110

The lug 16 projects into the slots 13 and engages the rear end walls thereof, whereby the slide is securely held in its adjustment against backward movement. The lug 16, which is approximately triangular, is beveled at the front and is provided with a rear shoulder, and the front end walls 18 of the slots are beveled to permit the lug to readily disengage itself from the slots 13, when the slide is drawn forward. The catch is also equipped with an outwardly extending finger or thumb piece 19, approximately L-shaped, and extending outwardly and rearwardly to a point slightly beyond the vertical eye 10 of the slide. This brings the operating portion of the catch in convenient position to be readily engaged by the thumb, whereby the slide may be instantly adjusted to change the position of the hold back with relation to the shaft. The L-shaped finger or thumb piece is preferably formed integral with the lug, being extended through a notch or recess 20 of the rear end of the spring 14. The rear end of the spring 14 is tapered, as shown, and the particular arrangement of the parts enables a much stronger spring than that shown in the said patent to be employed, thereby materially increasing the strength of the adjustable hold back.

30 The hinged half ring or coupling member is adapted to swing rearwardly or forwardly without affecting the operation of the catch, and when the hold back is swung forwardly to the position illustrated in dotted lines in 35 Fig. 3 of the drawing, a strain on it will readily move the slide forwardly along the guide. The catch will not interfere with the forward movement or adjustment of the slide along the guide, and it is only necessary 40 to manipulate the catch and withdraw the lug from engagement with the guide, when it is desired to adjust the hold back rearwardly along the shaft or thill.

Having thus fully described my invention, 45 what I claim as new and desire to secure by Letters Patent, is:—

1. An adjustable hold back of the class described including a longitudinal guide, a slide provided at opposite sides with flanges embracing the side edges of the guide, a catch mounted on the slide and engaging the guide to lock the slide against backward movement and arranged to permit a free forward movement of the slide, and a swinging coupling member hinged to the slide and lying entirely beyond the inner side of the shaft or thill.

2. An adjustable hold back of the class described including a longitudinal guide, bent at its ends to space its intermediate guiding portion from a shaft or thill, a slide provided at opposite sides with flanges embracing the side edges of the guide, a catch mounted on the slide and engaging the guide to lock the slide against backward movement and arranged to permit a free forward movement of the slide, and a swinging coupling member hinged to the slide and lying beyond the inner side of the shaft or thill. 60

3. An adjustable hold back of the class described including a longitudinal guide, a slide arranged on the guide and embracing the side edges thereof, a coupling ring or member hinged to the slide and lying wholly beyond the shaft or thill, and a catch carried by the 75 slide and arranged to engage the guide and having an operating portion extending partially through the swinging coupling member or ring.

4. An adjustable hold back of the class described including a guide provided at intervals with longitudinal slots, a slide mounted on the guide and provided with an eye, a catch consisting of a spring secured to the slide and provided with a lug extending 80 through the slide and arranged to engage the slots of the guide and having an exterior operating member projecting outwardly and rearwardly and terminating at the said eye, and a coupling member or ring extending 85 outwardly from the slide and mounted in the said eye.

5. An adjustable hold back of the class described comprising a longitudinal guide provided at intervals with slots and bent at its 90 ends to off-set its intermediate portion, spaced members located between the slots, fastening devices piercing the guide and the spacing members, a slide mounted on the guide, a coupling member or ring hinged to 100 the slide, and a catch including a spring secured at its front end to the slide, and a lug secured to the rear end of the spring and projecting through the slide and arranged to engage the guide bar and provided with an exterior operating piece arranged to extend 105 through the coupling member or ring.

In testimony, that I claim the foregoing as my own, I have hereto affixed my signature in the presence of two witnesses.

WILLIAM J. THOMAS.
